UNITED STATES PATENT OFFICE.

HENRY L. HUMPHREY, OF MONROE, MICHIGAN.

TROLLEY-WHEEL.

No. 866,363.

Specification of Letters Patent.

Patented Sept. 17, 1907.

Application filed October 12, 1906. Serial No. 338,534.

To all whom it may concern:

Be it known that I, HENRY L. HUMPHREY, a citizen of the United States of America, residing at Monroe, in the county of Monroe and State of Michigan, have invented certain new and useful Improvements in Trolley-Wheels, of which the following is a specification, reference being had therein to the accompanying drawings.

This invention relates to improvements in trolley wheels and more especially to trolley wheels of a construction similar to that shown in my application for Letters Patent filed Nov. 13, 1905, Serial No. 287,009; and the object of this invention is to so construct the bearing member upon which the wheel turns and secure it to the harp that it, together with the harp forms a rigid support for the wheel the parts of which support will not become loosened and detached by the vibration, and in which the bearing member is rigidly held from turning.

20 A further object of the invention is to provide a device having the several advantages of the particular construction, arrangement and combination of parts, all as hereinafter more fully described, reference being had to the accompanying drawing in which

25 Figure 1 is a side elevation of a device embodying the invention; Fig. 2, a transverse vertical section of the same; and Fig. 3 a top or plan view.

As shown in the drawings 1 is the harp or fork in which the trolley wheel is supported, said harp consisting of a socket portion 2 to receive the trolley pole and two arms 3 extending upwardly from said socket and curved outwardly away from each other so that should the wheel become disengaged in use, from the trolley wire, in pulling the pole downward to reengage the wheel therewith the wire will strike the outwardly curved side of one of the arms and be deflected so that it will not catch upon any projecting part of the trolley.

30 The upper enlarged ends of the arms 3 are each formed with a vertical slot 4 which is wider at the outer side of the arm than the inner side thereof, thus forming a dovetail slot to receive a dovetail 5 formed on each end of a shaft or bearing member 6. This member is further rigidly secured within the slotted 35 ends of the harp arms by pins 7 driven into transverse holes in the dovetails and arms. These arms are thus rigidly connected by the bearing member to form a rigid support for the wheel and said member is secured in such a manner that the vibration caused by the 40 rapid travel of the wheel on the wire will not loosen it, the strain being taken from the securing pins by the dovetail connection, and all possibility that the member may turn is removed.

45 The bearing member is formed all in one piece with a globular portion 8 intermediate its ends having a circumferential groove 9 which, in cross-section is V-

shaped with the apex cutting the surface of the globe and forming a narrow slot therein. The portions 10 of the member at each side of the globular part are cylindrical with the dovetails 5 formed on their outer ends. 60

The trolley wheel 11 is made in two parts, 12 and 13, the part 12 being formed with the wheel rim 14 having the groove for a trolley wire, cast integral therewith and also formed with a hub portion 15 forming one half of a socket to receive the globular enlargement of the bearing member, the other half being formed on the part 13 of the wheel. A short sleeve portion 16 extends laterally from each hub or socket portion 15 and each of said sleeve portions has an internal diameter which is greater than the diameter of 65 the cylindrical portions of the bearing member which they surround so that the rim of the wheel will have a limited lateral or wobbling movement, the wheel turning about the axis of the globular portion, said wobbling being limited by the contact of the sleeves 70 with the cylindrical portions 10. The bearing member being held from turning and the wheel turning upon its globular portion only, the bearing will wear the same at all points of contact and the wheel will run freely and there will be a good contact between the 75 surface after they have become worn considerably.

An annular oil chamber 17 surrounds the globular hub of the wheel, one half of the chamber being formed in each part of the wheel, which parts are secured together by bolts 18 passing through the web of the wheel 80 between the chamber and rim on the part 12 and through lugs 19 on the part 13. A strip of paraffined paper 20 or other suitable material is placed between the two parts to make a tight joint and said chamber communicates with the groove 9 through openings 21. 90 Oil is introduced into the oil chamber through a valve 22 screwed into a screw-threaded opening in the side of said chamber, said valve consisting of a tubular casing 23 open at one end and externally screw-threaded at its opposite end and formed at this end with an internal 95 valve seat for a valve 24 held to its seat by a coiled spring. When the casing is fully screwed in, its open end engages the opposite side of the casing and is tightly closed thereby, lateral openings 25 being provided in the casing to permit the escape of the oil admitted by the valve. 100

By forming the whole rim of the wheel integral with one part of the divided wheel, the cost of manufacture is reduced and the rim will wear much longer and give better contact than one made in halves. 105

Having thus fully described my invention what I claim is

1. The combination of a trolley harp having arms provided with longitudinal dovetail slots at its ends; a bearing member formed with a globular portion intermediate 110 its ends and having tenoned ends engaging said slots, means for securing the tenons of the bearing member in said slots comprising pins passing transversely through

63-3

- armed
bearing
member and tire
2. The combination of a trolley harp having arms provided at their outer ends with longitudinal dovetail slots, a journal having a globular central portion and cylindrical aligned arms with tenons engaging the harp slots, transverse pins through the arms and tenons, with a trolley wheel having a hub parted on its medial transverse plane, adapted to rotate and oscillate in a limited arc on the journal, a flange integral with one part of the hub offset from the wheel center, a peripherally grooved rim integral with the flange centrally disposed between the assembled hub ends, a flange on the other part of the hub offset sym-

metrically with the first flange and seated thereon at its 15 periphery, bolts securing the abutting portions of the flanges, an outwardly closing spring-seated oil valve through the latter flange communicating with the annular space between them, an inverted triangular peripheral groove in the globular portion of the journal and a central 20 groove in the assembled hub adapted to register with the journal groove.

In testimony whereof we affix our signatures in presence of two witnesses.

HENRY L. HUMPHREY.
